UNITED STATES PATENT OFFICE.

LEON COHEN, OF ST. LOUIS, MISSOURI.

HAT-LINING.

1,222,527.

Specification of Letters Patent. Patented Apr. 10, 1917.

Application filed July 30, 1914. Serial No. 854,048.

To all whom it may concern:

Be it known that I, LEON COHEN, a citizen of the United States, and resident of St. Louis, Missouri, have invented certain new and useful Improvements in Hat-Linings, of which the following is a specification containing a full, clear, and exact description, reference being had to the accompanying drawings, forming a part hereof.

10 My invention relates to improvements in hat linings, and it is the object of my invention to provide a hat lining with a flexible, horizontally disposed annular extension casing or flange having at its free margin

15 a continuous elastic element which flange and elastic element serve the functions of adapting or conforming a hat to different heads or coiffures, and of holding or retaining the hat in place without the use of pins

20 and the like, which pierce the hat, and which horizontal extension or flange reduces to a minimum the disturbance of hair arrangement or coiffure in the placing and removal of the hat on and from the wearer's head.

25 With the above purposes in view, my invention consists in certain novel details of construction and arrangement of parts hereinafter fully described, pointed out in my claim and illustrated by the accompanying drawing, in which Figure 1 is a simple sectional elevation of a hat having a lining constructed according to my invention;

Fig. 2 is an inverted plan of the hat shown in Fig. 1 with a portion of the lining in section; and

Fig. 3 is an enlarged fragmental section showing the detail of the horizontal extension and the elastic element therein.

Referring by numerals to the accompanying drawing:

4 designates the crown and 5 the brim of a hat, which in their specific construction form no part of my invention, and both of which may be varied infinitely as to configuration and relative dimensions, as fashion dictates.

Within the crown 4 is a flexible lining 6, "tacked" in place in an ordinary manner by stitches 7 at or adjacent its lower edge and near the brim 5 of the hat.

Departing now from the ordinary, I secure the lining 6 at a point above its lower

margin, and the stitches 7, by a line of stitches 8, and between the lines of stitches 7 and 8 fold, tuck or loop the lining to 55 provide an angular extension 9 of the lining or casing and secure the extension in its folded form by a line of stitches 10 at or adjacent the neck of the extension or casing, near the body of the lining. 60

Within this looped or folded extension of the lining I arrange an elastic cord 11, which is extended beyond its normal dimensions to exert an inwardly directed strain on the free margin of the extension, thereby holding it 65 normally in a substantially horizontal position with relation to the sides of the lining.

While I have shown the horizontal flange or extension as being a part of the lining, I do not wish to be understood as limiting 70 myself to this construction, as it is obvious that any other construction providing a flexible and elastic annular flange within the hat arranged at a substantially horizontal position relative to the sides of the hat will 75 perform the functions sought.

In placing a hat, having the device of my invention therein upon the head, it is obvious that the elastic and flexible flange will automatically conform to the wearer's head 80 or coiffure, and further that the elastic element will cling to the head and through the flange or lateral extension of the lining constitute a support for the hat which needs no extraneous securing devices, such as the common hat pins, thus obviating the deterioration and unsightliness due to constant prick 85 ing the sides of the hat crown by the insertion of hat pins.

In the provision of the extension, maintained at a definite angle with relation to the sides of the hat there is a minimum of surface bearing against the wearer's head, and hence there will be a minimum of hair or coiffure disturbance. 90

Having thus described my invention, what I claim as new therein and desire to secure by Letters Patent of the United States therefor, is:

In combination with a hat crown, a lining constructed of flexible material, means for securing the lining adjacent its lowermost margin to the hat crown; a second means, removed from the lower margin of

the lining for securing the lining to the crown, a fold in said lining between said securing means, securing means in said fold next adjacent the body of the lining, and an elastic element in said fold for the purposes stated.

In testimony whereof, I have signed my

name to this specification, in presence of two
subscribing witnesses.

LEON COHEN.

Witnesses:

R. G. ORWIG,
E. L. WALLACE.
